UNITED STATES PATENT OFFICE

ALFRED W. BRUCE, OF NEW YORK, N. Y.

LOCOMOTIVE BED AND SUPERSTRUCTURE

Application filed August 13, 1929. Serial No. 385,660.

This invention relates generally to beds for locomotives and more particularly to beds adapted to support a boiler of the steam and water tube type, and to housings 5 therefor.

Heretofore, the boilers usually employed in locomotive practice have comprised a staybolted portion surrounding the fire box and the combustion chamber, and a cylindrical barrel extending forwardly therefrom, provided with fire tubes. Such boilers are adapted to withstand only relatively low steam pressures. In my copending applications filed on even date herewith there is 10 described a novel high pressure boiler, comprising a tubular steam generator unit surrounding the fire box and the combustion chamber, and an economizer unit of the water tube type, disposed forwardly thereof, so as 15 to absorb the heat of the gases of combustion in their passage from the combustion chamber to the stack. This modern development has made advantageous radical changes in the structural details of locomotive beds and 20 superstructures, which changes are the subject of this invention.

An object of the invention is to provide a novel locomotive bed for supporting a steam generating apparatus.

Another object of the invention is to provide a locomotive superstructure adapted to be installed on or removed from a locomotive bed as a unit, or in sections, and comprising a smoke box, an economizer 35 housing, and a steam generator housing.

A further object of the invention is to provide a superstructure of the type indicated embodying covers for the generator and economizer which may be conveniently 40 opened to facilitate installation or removal of the units.

Another object of the invention is to provide a novel construction of locomotive bed, superstructure, generator, economizer, and 45 superheater, enabling the parts to be expeditiously assembled or disassembled.

A further object of the invention is to provide a locomotive bed embodying detachable side frames, and an integral structure embodying a body member adapted to support 50

the side frames in proper spaced relation, a cylinder saddle, cylinders, distribution valve chests, a cradle, a draw bar pocket, and pockets adapted to support a smoke box, a steam generator, and an economizer and 55 their housings.

Another object of the invention is to provide a locomotive bed of the type indicated, wherein the generator, economizer, and smoke box pockets are embodied in an integral casting separable from the remainder 60 of the bed.

A further object of the invention is to provide structures of the types indicated, which are of great strength and durability, and 65 which can be economically manufactured and maintained.

Other objects of the invention will herein-after readily appear.

The improvement claimed is hereinafter 70 fully set forth.

In the accompanying drawings: Figure 1 is a perspective view of a locomotive bed embodying the invention, one of the side frames being shown detached; Figs. 2 and 3, perspective views of a modified form of construction, respectively illustrating a separately formed member embodying the pockets for the superstructure and a separately formed main bed member; Fig. 4, a perspective view of the superstructure with the covers removed; Figs. 5, 6 and 7, perspective views, respectively, of a generator, a superheater, and an economizer of the type adapted to be housed and supported by the improved structure only the outer rows of tubes of the economizer and the superheater being shown; and, Figs. 8 and 9, perspective views, respectively, of the cover of the generator housing, and the cover of the economizer and 80 superheater housing.

In the practice of the invention, referring descriptively to the specific embodiment thereof which has been selected for exemplification herein, two main units are employed, 95 viz: a bed A and a superstructure B.

The bed A preferably embodies two detachable side frames 10, and an integral casting comprising a body member 11 to which the side frames are attached, a cradle 12, 100

smoke box and cylinder saddles 13, cylinders 14, distribution valve chests 15, a generator pocket 16, an economizer pocket 17, and a smoke box pocket 18.

6 The body member 11 is formed with parallel vertical side walls 11^a, having axle openings 11^b, a lateral longitudinal flange 11^c, on each side wall, and transverse vertical walls 11^d, connecting the side walls in the nature 10 of cross ties and spaced to form axle pockets.

Each side frame 10, is formed with a top rail 10^a, and pedestal jaws 10^b, and is adapted to fit against a side wall 11^a of the body member snugly beneath the lateral flange 11^c thereof. Any suitable means such as bolts, 16 keys, rivets, etc., may be employed to fasten the side frames to the body member. The pocket 16 for supporting a generator 19 and its housing, is formed at its rear end with a leg 16^a united to the cradle, and its front end is united to the body member 11. This pocket 20 comprises a vertical front wall 16^b, vertical side walls 16^c, and a horizontal bottom wall 16^d formed with a central opening 16^e for 25 an ash pan.

The pocket 17 for supporting an economizer 20 and a superheater 21 and their housing as of less width than the generator pocket 16, is formed with an imperforate horizontal bottom wall 17^a, disposed at a higher level, than the bottom wall 16^d of the generator pocket, and two parallel, vertical side walls 17^b.

The pocket 18, for supporting a smoke box 22, is of substantially the same width as the generator pocket, and is formed with parallel front and rear walls 22^a, 22^b, two parallel side walls 22^c, and a horizontal bottom wall 22^d, disposed at substantially the same level 30 as the bottom wall 16^d of the generator pocket.

The superstructure B, is formed of sheet metal, and comprises the smoke box 22, a housing 23, for the generator 19, and a housing 24 for both the economizer 20 and the superheater 21.

The generator housing 23, comprises a main portion 23^a, and a detachable transversely arched cover 23^b. The main portion 23^a, comprises, parallel vertical front and rear walls, 23^c, 23^d, two parallel vertical side walls 23^e, inverted U-shaped reinforcing bars 23^f, longitudinally disposed L bars 23^g, which provide flanges for attaching the cover, and longitudinally disposed L bars 23^h, which 35 provide flanges for attaching the housing to the generator pocket. The front wall 23^c, is provided with a suitable opening 23ⁱ for the passage of the gases of combustion.

The smoke box 22, is of oblong box shape, 40 and comprises parallel vertical front and rear walls 22^a, 22^b, two parallel vertical side walls 22^c, and horizontal top and bottom walls 22^d, 22^e. The rear wall 22^b, is provided with a suitable opening 22^f, for the passage 45 of gases of combustion. The economizer and

superheater housing 24 comprises a main portion 24^a and a detachable cover 24^b. The main portion comprises a bottom wall 24^c, two parallel vertical side walls, 24^d, and longitudinal L bars 24^e, which provide flanges for 70 attaching the cover. The cover 24^b is formed with an offset portion 24^f to accommodate the superheater 21. Any suitable means, such as bolting, riveting, welding, etc., may be employed to fasten the superstructure to the bed. 75

Figs. 2 and 3 illustrate a structural modification wherein the pockets for the generator, economizer and smoke box are formed in a separate integral casting adapted to be applied to another separately formed integral casting embodying a cradle, a body member, a smoke box saddle, cylinders, and distribution valve chests. 80

The improved construction provides a locomotive bed which is of great strength and durability, which can be economically manufactured and maintained, and which is adapted to support a generator, an economizer, a superheater, and a smoke box, formed as separate units. It further provides a housing which can be conveniently installed on or removed from the bed, and which enables either the generator, the economizer or the superheater to be expeditiously removed from or installed on the locomotive as separate units without dismantling the housing from the bed. It is within the contemplation of the invention to form the generator housing, the economizer housing, and the smoke box as separate units or to combine any two 95 of them as a unit.

While the steam generating apparatus described embodies a tubular generator and a water tube economizer, it is to be understood that the invention is equally applicable for use with boilers embodying a tubular fire box section and a fire tube section, and the term economizer, as used in the claims is intended to be sufficiently broad to include, as an equivalent, a fire tube boiler section. 110

While one of the preferred forms of construction has been shown, it is obvious that many variations in procedure, form, arrangement and construction of the parts, can be made, and the invention is not therefore limited to the particular embodiment disclosed, but includes such changes and modifications as come within the spirit and scope of the invention as set forth in the appended claims. 115

The invention claimed and desired to be secured by Letters Patent is:

1. A locomotive bed for supporting a smoke box unit, and steam generating apparatus comprising a tubular fire box unit and a water heater unit disposed intermediate the smoke box unit and the fire box unit, said bed being provided with a pocket for receiving one of the units. 125

2. A locomotive bed for supporting a smoke 130

- box unit, and a steam generating apparatus comprising a tubular fire box unit and a water heater unit disposed intermediate the smoke box unit and the fire box unit, said bed being provided with pockets for receiving at least two of the units. 5
3. A locomotive bed for supporting a smoke box unit, and a steam generating apparatus comprising a tubular fire box unit and a water heater unit disposed intermediate the smoke box unit and the fire box unit, said bed being provided with a pocket for receiving one of the units, formed as an integral casting. 10
4. A locomotive bed embodying a pocket for a steam generator and a pocket for a smoke box. 15
5. A locomotive bed embodying a pocket for a steam generator, and a pocket for an economizer. 20
6. A locomotive bed embodying pockets for an economizer and a smoke box. 25
7. A locomotive bed embodying pockets for a steam generator, an economizer, and a smoke box. 30
8. A locomotive bed comprising an integral casting embodying pockets for a steam generator and an economizer. 35
9. A locomotive bed comprising an integral casting embodying pockets for a steam generator, and a smoke box. 40
10. A locomotive bed comprising an integral casting embodying pockets for a steam generator, an economizer, and a smoke box. 45
11. A locomotive bed comprising an integral casting embodying a body member and an economizer pocket. 50
12. A locomotive bed comprising an integral casting embodying a cylinder saddle and a smoke box pocket. 55
13. A locomotive bed comprising an integral casting embodying a cylinder saddle, a cylinder, a distribution valve chest, and a smoke box pocket. 60
14. A locomotive bed comprising detachable side frames, and an integral casting embodying a cradle, and a steam generator pocket. 65
15. A locomotive bed comprising detachable side frames, and an integral casting embodying a cradle, a body member, a cylinder saddle, and a steam generator pocket. 70
16. A superstructure for locomotives detachable as a unit and comprising, a housing for a steam generator and a housing for an economizer. 75
17. A superstructure for locomotives, detachable as a unit comprising a smoke box, a housing for a steam generator, and a housing for an economizer. 80
18. A superstructure for locomotives, comprising a housing for an economizer and a housing for a steam generator, at least one of said housings having a cover adapted to be lifted to permit removal of the apparatus enclosed thereby. 85
19. In a locomotive, the combination of, a locomotive bed embodying a pocket for a steam generator, and a steam generator housing supported by the pocket. 90
20. In a locomotive, the combination of a locomotive bed embodying pockets for a steam generator an economizer and a smoke box, and housings for a generator and an economizer supported by the generator and economizer pockets, and a smoke box supported by the smoke box pocket. 95
